UNITED STATES PATENT OFFICE.

MICHAEL J. COLLINS, OF NEW YORK, N. Y.

DESIGN FOR AN UMBRELLA-STAND.

SPECIFICATION forming part of Design No. 25,645, dated June 16, 1896.

Application filed May 14, 1896. Serial No. 591,583. Term of patent 14 years.

To all whom it may concern:

Be it known that I, MICHAEL JAMES COLLINS, of New York city, in the county and State of New York, have invented and produced a new and original Design for an Umbrella-Stand, of which the following is a full, clear, and exact description.

Reference is to be had to the accompanying drawings, forming a part of this specification, in which similar characters of reference indicate corresponding parts in both the figures.

Figure 1 is a perspective view of a stand embodying my new design, and Fig. 2 is a side elevation therefor.
15 The design in its entirety consists of a base *a*, a back *b*, a top piece *c*, and ornamental vertical spindles *d* *d'* between the base and the top, said parts having the configuration shown. Thus the base *a* has a rounding front and a plurality of feet *a'*. Also centrally of the base there is a depression *a²* in the upper surface, the depression being surrounded by a ring *a³*, and at the lower side appears a cylindrical projection *a⁴*. The back *b* is plain except that it has an ornamental top, the latter having tapering sides presenting curved pro-

jections and depressions more or less of the ogee order. The top piece *c* has an open center, is rounding at the front and has acorn ornaments *c'* rising from its upper surface and a hemispherical protuberance *c²* at the front. The spindles *d* are located at the sides, and extend as continuous pillars from base to top piece, while the spindle *d'*, which is located at the front, depends from the top piece and terminates short of the base. All the spindles have enlarged portions or rings *d²* at intervals.

A leading feature of my design resides in the stand comprising the base, the back, the top piece and the vertical spindles between the base and the top piece.

Another leading feature is the continuous and pendent spindles between the base and the top piece of the stand.

45

I claim—

The design for an umbrella-stand herein shown and described.

MICHAEL J. COLLINS.
